UNITED STATES PATENT OFFICE.

ALVIN Q. WOLF, OF DAYTON, OHIO.

SASH-OPERATING MECHANISM.

No. 810,242.

Specification of Letters Patent.

Patented Jan. 16, 1906.

Application filed March 31, 1904. Serial No. 200,987.

To all whom it may concern:

Be it known that I, ALVIN Q. WOLF, a citizen of the United States, residing at Dayton, in the county of Montgomery and State of Ohio, have invented certain new and useful Improvements in Sash-Operating Mechanism, of which the following is a specification, reference being had therein to the accompanying drawings.

10 This invention relates to improvements in sash-operating mechanism designed especially for use in hot or green houses, where a number of sashes are employed.

15 The several essential objects of the invention and the devices by which these objects are carried into practice are, first, a system of hangers and braces attachable to the ridge-pole of the greenhouse-roof and adapted to support and brace operating mechanism at 20 either side of the ridge-pole, according to whichever side of the building the sashes are located; second, a system of operating-gears and sprocket-wheels adapted to be located in part at the end of the building and in part to be 25 suspended from the ridge-pole and working in conjunction with a peculiar cable, one branch of which operates the sash-rods and is supported from sagging, and, third, to numerous minor features of detail, all as hereinafter more fully described and particularly 30 pointed out in the claims.

In the accompanying drawings, forming a part of this application, and on which like reference-letters indicate corresponding parts, 35 Figure 1 is a side elevation of my operating mechanism, showing a partial interior view of a portion of a greenhouse with the apparatus applied thereto. Fig. 2 is a detail enlarged perspective view of a bracket used to 40 suspend the cable-supporting rods; Fig. 3, a detail enlarged perspective view of a sash-bar; Fig. 4, a detail enlarged perspective view of a sash-clip which may be used instead of the bar; Fig. 5, an enlarged side elevation 45 of one of the sash-bars; Fig. 6, a partial elevation and sectional view, on a still larger scale, of one of these bars; Fig. 7, an end elevation of the interior of a greenhouse, showing the operating devices for the cable also 50 in elevation; Fig. 8, an enlarged detail side view and partial sectional view of one of the supporting or hanging devices for the cable-sprocket; and Fig. 9, an end elevation of the 55 same parts, showing more particularly their relation to the ridge-pole of the roof.

The letter A designates a portion of a green or hot house with which my invention is specially designed to be used, although it is capable of use in other situations, and the letter B designates the ridge-pole, to which the 60 rafters C are connected at their upper ends. My apparatus is to be suspended at one end by suitable hangers from the ridge-pole and at the other is mounted upon a fixed column or post, but braced to the ridge-pole. The 65 hangers, specifically speaking, consist of a bar D, hung on a pivot-bolt E from a bracket F, bolted or otherwise secured to the ridge-pole. This bracket extends to one side of the ridge-pole in an angular direction, as seen 70 more clearly in Fig. 9, so that by turning the bracket end to it may be made to project from one side or the other, so as to suspend the hanging devices likewise to one side or the other. A brace G is connected by a 75 bracket H and bolts or screws to the bar D and is also connected by a bracket I of similar construction to the bracket F and adapted to be connected to the ridge-pole and to extend to one side thereof, as in the case of 80 the bracket F. The connection between the brace G and the bracket I is preferably pivotal by means of a bolt J. To the lower end of the bar D is secured a plate K, to which is pivoted a bearing-lever L, the supporting 85 sprocket-wheel M being mounted eccentrically for a purpose hereinafter named on this lever at its lower end, while its other end is adjusted by a nut and bolt N, so as to take up the slack and create sufficient tension in 90 the operating-cable composed of sections of sprocket-chains O and P and intermediate sections of rods Q.

At suitable points along the greenhouse and to the frame thereof—say to the under 95 side of the ridge-pole—brackets R are secured, having a number of holes S, into either of which a cable-brace T is hooked at its upper end, while its lower end engages one of several holes in a clip U, secured to the 100 lower cable-rod Q. A second cable-brace V is engaged with a staple or eye W, supported by one of the rafters, and also with one of the openings in the clip U. The upper ends of these cable-braces T and V are somewhat 105 separated, while their lower ends are quite close together, and they are so situated that they will allow the cable to be adjusted in either direction, swinging on their pivots as the cable moves. Their purpose is to brace 110

the cable against swaying off to one side when the sash rods or lifters X are exerting a force in lifting or holding open the sashes to which at one end they are connected, while at 5 the other they engage with one of the openings in the bracket U. The position of the sash lifters or rods is at an angle to the rafters, so that when the lower end of the same is moved by the cable the sashes will be lifted or lowered according to the direction of movement. The sashes are indicated at Y, and the connection of the rods or lifters X therewith may be either through the sash-bars Z, which are secured to the sides of the 10 sash-frame and have openings a, in either of which an eyebolt b is secured for connection with such rods or lifters, or by means of a sash-clip c, designed to be secured to the lower bar of the sash-frame and having an opening, in which is secured the eyebolt b for the purpose stated. Either this sash-bar or sash-clip may be used, according to the weight of the sash or the particular situation. It will now be seen that the sashes are 15 controlled by these rods or lifters X and that the cable is braced at the points of attachment of the rods therewith, yet that the cable is free to be adjusted longitudinally back and forth. This brings me to a description of the mechanism employed to operate this cable. It consists of a column or post d—say in the nature of a stout pipe—secured at its lower end to a post or part of the frame e by a clip f, and at its upper end secured to the ridge-pole by a 20 short arm g, which may be turned on the column d, so that the column may be set to either side of the ridge-pole, while the arm extends over to the pole. This column carries a stout bearing-plate h, clamped to the 25 column by means of a clip i and bolts j. This bearing-plate h carries a reversible fork k, connected thereto by bolts and nuts l and bolted to a brace m, which extends up and is secured to the ridge-pole. As seen from Fig. 7, 30 this reversible fork k extends to one side of the column d, so that although the brace m is directly under the ridge-pole it connects with and braces the column and bearing-plate which stand to one side of the ridge-pole. This brace m and fork k, together with the hanger D G, constitute the hanger and brace devices referred to hereinbefore.

By reason of the construction which I have 35 described the operating mechanism may be laterally offset to either side of the vertical plane of the ridge-pole, and the cable may be correspondingly offset so as to bring it more directly under the sashes. This position of the cable is obviously advantageous, for the 40 reason that excessive lateral thrust on the cable is avoided and the connections between the cable and sashes may be materially shortened, while the movements of said connections are more nearly in the plane of movement imparted to the sashes.

Referring now specifically to the cable-operating mechanism, it will be seen that in the bearing h there is mounted a shaft n, carrying a sprocket-pinion o and a bevel-gear-wheel p. On this sprocket-pinion is mounted the sprocket-chain P, so that when the pinion is rotated in one direction or the other the entire cable is moved in one direction or the other. The parts are so adjusted that the sashes will be lifted to their extreme open 75 position when the stop q on the lower branch of the cable comes into contact with one of the teeth of the pinion o, and so that the sashes will be in their closed position when the stop r on the lower branch of the cable 80 comes into contact with one of the teeth of the pinion o. A bevel-pinion s meshes with and drives the bevel-gear p, and as the pinion o is united to the bevel-gear p rotary motion is thus given said pinion. The 85 bevel-pinion s is mounted upon an operating-shaft t, having a bearing at its upper end in a yoke u, suspended on the ends of the shaft n. The lower end of the shaft t is mounted in a lower bearing-plate v, held to the column d 90 by means of a clip w and nuts and bolts x. This bearing-plate v also carries a fixed stud-shaft y, on which is mounted a hand-wheel z, carrying a bevel-pinion z' and a ratchet-wheel y'. This bevel-pinion meshes with a 95 crown-wheel t' on the lower end of the shaft t. By these devices rotary motion is imparted to the operating-shaft t, and thence to the other parts, as above indicated. To lock the parts in any adjusted position, a pivoted detent x' 100 is dropped into the ratchet-wheel y'. An arm w', carried by the stud-shaft y, supports the detent x'.

Referring again to the detail character of the construction of the sash-rods X, attention 105 is directed to Figs. 5 and 6, wherein this rod is shown in detail. It will be seen that it is divided into two parts, one of which, X', is hollow to receive the other part, while any one of the series of holes in the part X' will receive a pin Y', the pin passing through a hole in the other part of the rod, whereby the length of the entire rod may be made greater or less to suit the particular situation where the apparatus may be mounted.

The mode of operation of my apparatus 110 will now be understood, and I need only therefore add that it is effective in use and safe and reliable in its control over and adjustment of the sashes, both with regard to 115 holding them open or partly open and holding them closed. The sprocket-wheel M being mounted eccentrically, as before stated, and as shown in Fig. 1, it will be seen that as the lower branch of the rod or cable moves 120 to the left the wheel will revolve, bringing the shorter or minor radius thereof over to the right, thereby lengthening the cable and compensating for the arc described by sash-rods 125 X as they swing to lift the sashes. As shown 130

in Fig. 1, the sashes are partly up and the stop *q* and wheel *M* are in corresponding positions.

Having thus fully described my invention, 5 what I claim as new, and desire to secure by Letters Patent, is—

1. In a sash-operating apparatus, the combination, with an inclosing structure comprising a ridge-pole and sashes, of a hanger 10 connected with said ridge-pole, an upright, brace devices connected with said pole and upright, said hanger, upright and brace devices being located below the ridge-pole and laterally offset with respect to the vertical 15 plane thereof, a cable, sash-rods directly connecting said cable with the sashes, to which their ends are respectively pivoted, supporting-wheels for said cable carried by said hanger and by said upright and brace devices 20 respectively, and operating devices to rotate one of said wheels in either direction, substantially as described.

2. In a sash-operating apparatus, the combination, with hanger and brace devices, and 25 reversible devices for supporting them at either side of a fixed part of the structure, of a cable, sash-rods connected thereto and adapted for connection with the sashes, supporting-wheels for said cable carried by said 30 hanger and brace devices, and means to operate one of said supporting-wheels in either direction.

3. In a sash-operating apparatus, the combination, with a hanger, and brackets to connect it with a ridge-pole, of a wheel carried by said hanger, a column and brace devices to connect it with a house structure, a bearing-plate carried by the column and having mounted therein another supporting-wheel 40 and operating-gears, hand-operated gears connected with the first-named gears, a cable mounted on the supporting-wheels, and brace-rods and sash-lifters connected with the cable and adapted respectively to connect with the house structure and the sashes. 45

4. In a sash-operating apparatus, the combination, with a column, of a bearing-plate connected thereto, a shaft in said bearing carrying a bevel-gear and a sprocket-wheel, a 50 driving-shaft connected to said bearing and having a pinion meshing with said gear, an-

other bearing-plate connected to the column and carrying a hand-operated pinion, and a gear-wheel meshing with said pinion and mounted on the driving-shaft.

55

5. In a sash-operating apparatus, the combination, with a column, of a bearing-plate connected thereto, a reversible fork connected to the bearing-plate and having a brace adapted for connection with a ridge-pole, and 60 an arm on the column similarly adapted for connection with the ridge-pole, whereby the column and the parts it sustains may be held to, but at one side, of the ridge-pole.

6. In a sash-operating apparatus, the combination, with a ridge-pole and a hanger including a brace, of reversible brackets connected with the hanger and brace and adapted for connection with the ridge-pole, the reversibility of the brackets acting to sustain 70 the hanger and braces at either side of such pole.

7. In a sash-operating apparatus, the combination, with a hanger, of a lever pivoted thereto, a cable-supporting wheel carried by 75 the lever, and means to adjust the lever to vary the position of said wheel to affect the tension of the cable.

8. In a sash-operating apparatus, the combination, with a hanger and brace devices 80 adapted for connection with a house structure, of a cable, sash-rods connected thereto and adapted to connect with the sashes, supporting-wheels for said cable carried by said hanger and brace devices, and operating devices to rotate one of said wheels in either direction, the other wheel being eccentrically mounted to lengthen the cable so as to compensate for the arc described by the sash-rods when the sashes are being lifted. 85

9. In a sash-operating apparatus, the combination, with a sash-operating cable, sash-rods secured to the cable and to the sash, wheels upon which the cable is carried, one of them being eccentrically mounted for the 95 purpose set forth.

In testimony whereof I affix my signature in presence of two witnesses.

ALVIN Q. WOLF.
